DUSTPAN MANIPULATOR FOR CARPET SWEEPERS

Carl C. Parrish, Shelbyville, Ind., assignor to Porter Steel Specialties, Shelbyville, Ind., a co-partnership composed of Hester Porter Fuller, George M. Parker, and Parrish Fuller

Application February 7, 1940, Serial No. 317,650

2 Claims. (Cl. 15—41)

The object of my invention is to provide an efficient means by which the dust pans of a carpet sweeper of the rotary-brush hand-operated type may be readily operated to discharge their contents, the construction being such that the exposed operating element, though readily accessible, will be inconspicuous and cannot be contacted against furniture, and such, that it can be incorporated in the sweeper at low cost.

The accompanying drawing illustrates my invention.

Fig. 1 is a perspective view of an embodiment of my invention;

Fig. 2 an end elevation with the external cover plate removed;

Fig. 3 a fragmentary sectional plan; and

Fig. 4 a vertical section on line 4—4 of Fig. 1.

In the drawing 10 indicates the usual end wall of the main casing or shell of a sweeper of this type, conveniently made of ply-board. Formed in one vertical face of this end board (the outer face in the present illustration) is a groove 11 which opens through a side wall 12 of the casing at one end, and extends to the middle of the end wall where it communicates with a vertical slot 13 extending through the end wall.

Journalled in groove 11 is a shaft 14 provided, at its inner end, with an inwardly-extending lever 15 and, at its outer end, provided with a manipulating lever 16 extending close along the outer face of side wall 12 immediately above the usual rubber buffer ring 17 which surrounds the main casing. Lever 16 normally lies below the top of the casing and is conveniently bowed upwardly, as shown, so as to provide adequate finger room between it and the buffer ring. Lever 16 is conveniently encased in a rubber thimble 18.

The inner end of lever 15 is connected to the apex of the usual V-spring 20, the opposite ends of which are hooked into the heels of the usual dust pans 21 which are pivoted in the main casing on horizontal axes 22.

As usual in structures of this type, the opposite ends of the dust pans are provided with a similar V-spring and the two V-springs perform their usual function of normally holding the dust pans in receiving position.

In order to retain shaft 14 in groove 11 a thin metal retaining strip 25 is nailed in place over the groove and shaft.

An upward force on lever 16 causes upward movement of the inner end of lever 15 and its connected V-spring 20 to cause a dumping swing of the dust pans.

The groove 13 may be formed at low cost and provides an efficient journal for shaft 14. As lever 16 lies closely above the buffer ring 17 and below the top of the casing, it is very inconspicuous and is thoroughly guarded so that it cannot be brought into contact with furniture.

In many instances the debris which is accumulated in the dust pan does not discharge readily when the pans are thrown to open position and the operator desiring complete discharge must sweep the pans with a brush, cloth or fingers. To facilitate this operation the amplitude of swing of shaft 14 and the length of its lever 15 is such that the pans, on their opening movement, may have their heels brought against stops 26 which, while preventing the points of attachment of the ends of spring 20 from passing dead center, nevertheless permit said points to so nearly approach dead center that the springs, of their own resilience, are incapable of automatically closing the pans but permit initial closing movement of the pans by application of an initial returning force on lever 16.

In order to insure proper relation of springs 20 and lever 15 at all times, the apex of the spring is slightly elongated, as shown in Fig. 4, so that it may not be accidentally displaced relative to lever 15. The spring may be thus formed without additional cost and without hindering threading the spring through the eye of lever 15, thus contributing to low cost of production and assembly.

It will, of course, be understood that the above described invention may be readily employed in a sweeper having a sheet metal casing and that, in its broadest aspect, the distinguishing characteristic is an oscillable pan manipulating shaft journalled on the end wall of the casing on an axis parallel with the end wall and provided, at one end, with a crank arm engaging the pan spring or lifting link and, at the other end, with a manipulating crank arm.

I claim as my invention:

1. In a sweeper having dust pans mounted to be swung about two axes to and from retaining and discharging positions, a V-spring having its free ends anchored respectively on the pans between the two axes of the pans and resiliently acting on said pans normally to move said pans to and hold them in debris retaining position, and operating means by which said V-spring may be positively bodily shifted alternately, toward and from the pan plane, pan arresting means arranged to permit but limit pan open-

ing movement to a position where the V-spring by reason of its resilience is incapable of initiating return movement of the pans but such return movement may be initiated by application of force upon the V-spring by said operating means.

2. A carpet sweeper having a main casing comprising a top and depending side walls and end walls, one of said end walls having an open groove formed in its outer face and extending in a plane at right angles to a side wall and terminating in a perforation through said side wall, a rock shaft journaled in said groove and pro-

vided at its inner end with a lever arm projected through said perforation into the interior of the casing and provided at its outer end with a laterally extending operating arm projecting in the same direction and overlying the exposed face of the adjacent side wall of the casing, a pair of swinging dust pans pivotally supported within the casing between its end walls, and a push-and-pull connection between the lever arm of the rock shaft and each pan between its axis and the medial transverse plane of the casing.

CARL C. PARRISH.
